UNITED STATES PATENT OFFICE.

CHARLES ROSAT, OF BOUDRY, SWITZERLAND.

APPARATUS FOR POLISHING THE PIVOTS OF ESCAPEMENTS AND OTHER CLOCK-WHEELS.

1,235,503.

Specification of Letters Patent. Patented July 31, 1917.

Application filed November 19, 1913. Serial No. 801,785.

To all whom it may concern:

Be it known that I, CHARLES ROSAT, a citizen of the Swiss Republic, and resident of Boudry, Canton of Neuchâtel, Switzerland, have invented a new and useful Apparatus for Polishing the Pivots of Escapements and other Clock-Wheels, of which the following is a full, clear, and exact specification.

10 The object of the present invention is to provide ways and means for polishing the pivots of escapements and other clock wheels easily, quickly and perfectly, also to render it capable of being effected by any 15 one not very expert. The apparatus which forms the subject matter of the invention is so arranged that without worrying about the final diameter of the pivot and the further operations the polishing steel has simply 20 to be worked backward and forward while all other precautions are taken care of by the apparatus itself. This apparatus is characterized by the feature that the pivot to be polished, fixed on one side in a rotating 25 holder of known kind, is carried with its thicker body portion in an indented bearing adjustable according to the thickness of the pivot so as to have its indentation in one line with the axis of the latter, while the 30 polishing steel has its back surface supported upon an abutment arranged to give the working pressure by spring or weight means and is held by this against the work piece (pivot) until it contacts with an adjustable stop adjusted in accordance with the 35 final diameter of the pivot in such a way that with the pivot quite free, it allows of uniform and complete circular polishing of the pivot to the desired diameter merely by 40 working the polishing steel backward and forward. When the pivot bearing and the polishing steel stop are once adjusted, no attention need be paid to the remaining stages of the work; the working pressure 45 is automatically exerted and need no longer be left to the mere feeling of the operator; the pivot is uniformly polished along its whole length; the central guiding of the pivot during its rotation is insured by the 50 indented bearing and keeping to the desired diameter is insured by the stop for the polishing steel preferably consisting of a micrometer screw.

The drawing illustrates one example of

construction of the subject matter of the 55 invention.

Figure 1 is a front view,

Fig. 2 a side view, and

Fig. 3 a plan of the apparatus.

Fig. 4 illustrates an escapement and shows 60 particularly the shape of the pivot of the same.

A holder or chuck *c* of known construction is rotatably mounted in the cheeks *a* of the frame *b* of the apparatus. This chuck *c* 65 which is driven by any means through a grooved pulley, consists, for example, of three clamping jaws which may be opened by pressing on a knob *d* and may be closed by the action of a spring on releasing said 70 knob. The escapement or the clock wheel is fixed in the chuck *c* by one pivot while the other freely projecting rough pivot to be polished is laid with its thicker body portion marked *z* in Fig. 4 in an indented bearing 75 plate *f*. The latter is fixed removably upon the top piece *e* of an arm *g* which can be raised and has a broad supporting part mounted in two cheeks *h* of the frame *b*. The position of the bearing plate *f* and its 80 notch or indentation relatively to the axis of rotation of the chuck *c* is determined by a micrometer screw *i* which is screwed into the arm *g* and upon pressing on the thumb piece *j* of the arm *g* insures the central and 85 steady rotation of the escapement under the drive of the chuck *c*.

A vertical abutment bolt *k* is mounted in the frame *b*, the upper end of which is beveled off and which is by means of a helical 90 spring *l* (Fig. 2) pressed steadily upward. The uppermost position of this bolt *k* is limited by an underneath stop head *m*. The bolt *k* serves as an abutment for a polishing steel *n* shown in Figs. 1 and 2, acting either 95 through an abrasive or provided with a file-like surface and which lies with its back surface on the upper beveled edge of the bolt and upon this is worked to and fro, bearing from below against the free escape- 100 ment pivot so that the working pressure necessary for the polishing is exerted by the pressure spring *l* operating on the abutment bolt. A micrometer screw *o* serving as a stop for the polishing steel and which is 105 screwed into the top piece *e*, determines in an adjustable manner the final diameter to which the rough pivot is to be polished.

In order to polish the freely projecting rough pivot as well as the conical joining part it is sufficient to draw the polishing steel *n* to and fro in its longitudinal direction 5 upon the upper edge of the supporting bolt *k* during the rotation of the chuck *c* until when the steel *n* contacts with the screw stop *o* the polishing is completed to the desired diameter.

10 By raising the arm *g* and the parts carried by it the escapement or the like may conveniently be fixed in position and examined.

What I claim is:

- 15 1. An apparatus for polishing the pivots of escapement and other clock wheels, comprising in combination a rotatable holder for holding the work piece with the pivot to be polished in a freely projecting condition, an adjustable indented bearing for receiving in its indentation the thicker body portion of the pivot, a movable polishing steel, a vertically movable abutment for supporting the polishing steel to be moved to 20 and fro on said abutment, pressure means 25 yieldingly acting upon said abutment to raise it and to thus press the polishing steel with its working face from below against the pivot to be polished and an adjustable stop adjusted according to the final diameter of the pivot and designed to limit the upward movement of the polishing steel under the action of said pressure means, substantially as and for the purpose described.
- 30 2. An apparatus for polishing the pivots of escapement and other clock wheels, comprising in combination a rotatable holder for holding the work piece with the pivot to be polished in a freely projecting condition, an adjustable indented bearing for receiving in its indentation the thicker body portion of the pivot, a movable polishing steel, a vertically movable abutment bolt for supporting the polishing steel to be moved to 35 and fro on said abutment bolt, spring means 40 acting upon said abutment bolt to raise it and to thus press the polishing steel with its working face from below against the pivot to be polished and an adjustable stop adjusted according to the final diameter of the pivot and designed to limit the upward movement of the polishing steel under the action of said pressure means, substantially as and for the purpose described.
- 45 3. An apparatus for polishing the pivots of escapement and other clock wheels, comprising in combination a rotatable holder for holding the work piece with the pivot to be polished in a freely projecting condition, an adjustable indented bearing for receiving in its indentation the thicker body portion of the pivot, a movable polishing steel, a vertically movable abutment bolt for supporting the polishing steel to be moved to 50 and fro on said abutment bolt, spring means acting upon said abutment bolt to raise it and to thus press the polishing steel with its working face from below against the pivot to be polished and an adjustable stop adjusted according to the final diameter of the pivot and designed to limit the upward movement of the polishing steel under the action of said pressure means, substantially as and for the purpose described.

eter of the pivot and designed to limit the upward movement of the polishing steel under the action of said spring means, substantially as and for the purpose described.

3. An apparatus for polishing the pivots 55 of escapement and other clock wheels, comprising in combination a rotatable holder for holding the work piece with the pivot to be polished in a freely projecting condition, an adjustable indented bearing for receiving in its indentation the thicker body portion of the pivot, a movable polishing steel, a vertically movable abutment bolt beveled off at its upper end and arranged to support the polishing steel to be moved to 60 and fro on said abutment bolt, spring means acting upon said abutment bolt to raise it and to thus press the polishing steel with its working face from below against the pivot to be polished and an adjustable stop adjusted 65 according to the final diameter of the pivot and designed to limit the upward movement of the polishing steel under the action of said spring means, substantially as and for the purpose described.

4. An apparatus of the character described having in combination a rotatable work holder, a support for polishing means movable transversely to the rotative axis of the work holder and engageable with the work held thereby to polish the same, and an adjustable stop for limiting the movement of said polishing means toward the work.

5. An apparatus of the character described having in combination a rotatable work 85 holder, a support for polishing means movable transversely to the rotative axis of the work holder and engageable with the work held thereby to polish the same, a stop for limiting the movement of said polishing 90 means toward the work, and a micrometer screw for adjusting said stop.

In witness whereof I have hereunto signed my name this 27th day of October 1913, in the presence of two subscribing 95 witnesses.

CHARLES ROSAT.
